[57] CLAIM

The ornamental design for a temporomandibular joint prosthesis, substantially as shown and described.

DESCRIPTION

FIG. 1 is a perspective view of a temporomandibular joint prosthesis showing our new design;

FIG. 2 is a bottom plan view thereof;

FIG. 3 is a top plan view thereof;

FIG. 4 is an inside view thereof;

FIG. 5 is a front elevational view thereof;

FIG. 6 is an outside view thereof;

FIG. 7 is a back elevational view thereof;

FIG. 8 is a perspective view of a second embodiment of the temporomandibular joint prosthesis;

FIG. 9 is a bottom plan view thereof;

FIG. 10 is a top plan view thereof;

FIG. 11 is an inside view thereof;

FIG. 12 is a front elevational view thereof;

FIG. 13 is an outside view thereof; and

FIG. 14 is a back elevational view thereof.
